UNITED STATES PATENT OFFICE.

WILLIE E. DEWEY, OF RACINE, WISCONSIN.

PILLOW-SHAM HOLDER.

SPECIFICATION forming part of Letters Patent No. 318,966, dated June 2, 1885.

Application filed August 4, 1884. (No model.)

To all whom it may concern:

Be it known that I, WILLIE E. DEWEY, of Racine, in the county of Racine and State of Wisconsin, have invented certain new and useful Improvements in Pillow-Sham Holders; and I do hereby declare the following to be a full, clear, and exact description of the invention, such as will enable others skilled in the art to which it appertains to make and use the same.

My invention relates to an improvement in pillow-sham holders.

Hitherto it has been customary to construct holders in such a manner that the sham is rolled or folded in removing it from the pillow, or requires to be handled in being so removed.

The object of my present invention is to provide a sham-holder which shall automatically remove the shams from the pillows; a further object being to provide a sham-holder which shall hold the sham by one edge, thereby allowing the same to hang perfectly flat without the necessity of handling; a further object being to provide a holder which shall swing from one post, and which is convenient and durable.

With these ends in view my invention consists in certain features of construction and combinations of parts, as will be hereinafter described, and pointed out in the claims.

In the accompanying drawings, Figure 1 is a view in perspective of my improved holder with sham in position on the pillow, and Fig. 2 is a view in front elevation of the same when shams are removed from the pillow, and Fig. 3 is a detached view of bracket.

A and B represent the head-posts of bedstead. To either post A or B, as may be found convenient, a bracket, C, is secured, preferably by means of a screw, c, and a screw-eye, c'. The bracket C may be of any desired form or material, and is provided with two projecting lugs or ears, D, to which the swinging arm E is hinged by means of the pintle d.

The swinging arm E is provided with a socket, e, adapted to receive the end of a pole, F, and with a supporting-shoulder, e'. The pole F is conveniently secured to the arm E by a screw passing through the head of the socket e into its end and a screw passing through the shoulder e' into its side.

The pole F is adapted to hold the sham or

shams by the upper edge, and may be provided with tape, a leather strip, a clamp, or any other suitable and convenient device for securing the edge of the sham thereto. The pole F is provided near its outer end with an eye, h, by means of which it is locked to a hook, H, the latter being secured to the head-post not having the bracket C secured thereto.

The pole F, with the shams hanging therefrom, is thrown outward and held from the head of the bed by the tension of a spiral spring, G, about the pintle d, and is swung back to its position across the head of the bed, when desired, by means of a cord, g, one end of which is secured to the pole a short distance from the hinge, and passing from thence through the eye c', thence back through an eye, g', secured to the pole F, and thence to the hook H. By pulling on the cord g the pole will be drawn to its position across the head of the bed and locked in this position by placing the eye or ring h over the hook H. The shams will now occupy the required position over the pillows, and when it is desired to remove them therefrom the eye h is released from the hook H, and the tension of the spring G will swing the pole and shams off to the side of the bed.

It is evident that slight changes may be made in the form and arrangements of the several parts described without departing from the spirit and scope of my invention; hence I do not wish to limit myself strictly to the description herein set forth; but,

Having fully described my invention, what I claim as new, and desire to secure by Letters Patent, is—

1. In a pillow-sham holder, the combination, with a head-post of a bedstead, of a horizontally-swinging pole hinged thereto, substantially as set forth.

2. In a pillow-sham holder, the combination, with a bracket secured to a head-post, of a sham-supporting horizontally-swinging pole hinged thereto, and a cord for operating the same, substantially as set forth.

3. In a pillow-sham holder, the combination, with a bracket secured to a head-post, of a spring-actuated horizontally-swinging pole hinged to said bracket, substantially as set forth.

4. In a pillow-sham holder, the combina-

tion, with a bracket secured to one of the head-
posts, and a pole journaled on said bracket
and adapted to swing in a horizontal plane, of
a spring for swinging or forcing the pole to
one side, or away from the bed.

5. In a pillow-sham holder, the combina-
tion, with a horizontally-swinging sham-sup-
port operated by a spring and cord, of de-
vices for locking the support in position across
to the head of the bed, substantially as set forth.

In testimony whereof I have signed this
specification in the presence of two subscrib-
ing witnesses.

W. E. DEWEY.
